UNITED STATES PATENT OFFICE.

JOSEPH SACHS, OF HARTFORD, CONNECTICUT.

LOCKING MEANS FOR INCLOSED ELECTRIC SWITCHES.

Application filed February 2, 1922. Serial No. 533,733.

To all whom it may concern:

Be it known that I, JOSEPH SACHS, a citizen of the United States, residing at Hartford, in the county of Hartford and

5 State of Connecticut, have invented a new and useful Improvement in Locking Means for Inclosed Electric Switches, of which the following is a specification.

In inclosed switches, that is those switches 10 in which the stationary and movable conductors are sealed in a casing and are operated for opening and closing the circuits from the exterior, it is desirable to limit the throw of the movable conductors and also 15 to be able to lock the operating spindle with the circuits open. This invention relates to those means which are applied to the inside of the casings of such switches for limiting or locking the operating 20 spindles.

The object of the invention is to provide a very simple, cheap and easily manipulated means for limiting the movement of or for locking the operating spindle, which 25 means is so constructed and arranged that the cover of the casing cannot be closed and sealed unless said means is in correct position to perform the function desired.

This object is attained in the embodiment 30 of the invention illustrated by pivoting a latch on the inside near the edge of the casing which latch has a part that extends into the path of a section of the spindle in the casing and a part that projects to the 35 outside of the casing into the path of the edge of the cover in such manner that if the latch is not in approximate stopping or locking position the cover is obstructed by it and cannot be closed and if the latch is 40 in approximate but not ultimate position, closing the cover will force it to correct position to properly perform its function.

In the accompanying drawings Figure 1 shows a plan of an inclosed switch with the 45 cover omitted, that is provided with an embodiment of the invention. Fig. 2 is a section of the same on the plane indicated by the dotted line 2—2 on Fig. 1 with the cover closed and the latch in stopping position. Fig. 3 shows on larger scale the co- 50 operating parts with the latch in stopping position. Fig. 4 is a similar view with the latch in locking position. Fig. 5 shows an edge view of the co-operating parts. Fig. 55 6 is a view showing in full lines the latch

turned into such position that the cover cannot be closed, and in dotted lines positions of the latch in which it will be forced to place by the closing of the cover.

The particular type of switch mechanism 60 is not essential to this invention. That which is illustrated has two conductors 1 pivoted to conducting ears 2 and adapted to be swung into and out of engagement with conducting ears 3. These parts are mounted 65 on an insulating base block 4 that is secured to the back wall 5 of the metal enclosing case. Attached to the movable conductors are plates 6 of insulating material provided with notches 7.

The operating spindle is rotatably supported by the opposite side walls 8 of the casing. On the exterior the spindle has a handle section 9 and on the interior has a crank section 10 that engages the notches in 75 the insulating plates which are fastened to the movable conductors. Turning the handle on the exterior imparts a rotatory movement to the crank on the interior and this throws the movable conductors in the manner common to this type of switch.

Pivotedly mounted on the inside of one of the casing side walls near the edge is a latch 11. The free end of the latch has a lug 12 that extends inwardly into the plane 85 of the path of the spindle crank. When the latch is turned to the position shown in Fig. 3 the lug forms a stop which engages the crank and limits the opening movement of the conductors. With the latch in the 90 position shown in Fig. 4 the lug extends in front of and prevents the spindle crank from being turned so as to throw the movable conductors into engagement with the stationary conductors. The latch moves 95

close to the side wall of the casing. Fasted to the latch and extending outward across the edge of the casing and into the path of the edge of the cover 13 is a headed stud 14. A notch 15 is cut in the edge of the casing and when the latch is turned to position to properly perform the desired function the stud will lie in the notch. An indentation 16 may be struck in from the side wall so as to project into the path of the latch and prevent the accidental movement of the latch from stopping or locking position. The latch may be oscillated when sufficient force is applied to move it past this indentation.

If the latch is turned over and left in the position shown in full lines in Fig. 6 the cover cannot be closed down to the box for the edge of the cover engages with an is held 5 from closing by the stud that projects from the latch. Should the latch be left approximately in stopping or locking position as illustrated by the dotted lines in Fig. 6 the edge of the cover engages with the stud 10 and turns the latch down and forces it into proper position before the cover can be closed and secured. When the cover is closed and fastened the latch cannot be moved.

15 The invention claimed is:

1. An inclosed switch comprising an enclosing case, switch operating means, and means adapted to be moved into position to limit the movement of the switch operating means, said limiting means having a part that projects into the path of the edge of the cover whereby the cover can not be closed tightly unless said limiting means is in position to perform its function.

2. An inclosed switch comprising an enclosing case, switch operating means supported within the case, and means pivotally connected with the wall of the case and adapted to be swung into position to limit 30 the movement of the switch operating means or to lock the switch operating means against movement, said limiting and locking means having a part that projects to the exterior of the case into the path of the edge of the cover whereby the cover can not be closed tightly until the said limiting and locking means is in position to perform its required function.

3. An inclosed switch comprising an enclosing case, switch operating means, and pivoted means adapted to be swung into and out of engagement with the switch operating means on the interior of the case, said means having a projection extending to the exterior of the case into the path of the cover and adapted to be engaged thereby, and preventing the closing of the cover unless the pivoted means in the interior is in position to be engaged by the switch operating means.

4. An inclosed switch comprising an enclosing case, switch operating means supported by the walls of the case, means pivoted to the inside of the side wall of the case and adapted to be swung into and out of locking or stopping engagement with the switch operating means on the interior of the case, said means having a projection extending to the exterior of the case into the path of the edge of the cover and adapted to be engaged thereby.

5. An inclosed switch comprising an enclosing case, a switch operating crank spindle supported by the walls of the case, a pivoted latch in the case, said latch hav-

ing a part adapted to engage a portion of the crank spindle in the interior of the case, and a part adapted to be engaged by the edge of the casing cover on the exterior of the case.

70

6. An inclosed switch comprising an enclosing case, a switch operating crank spindle supported by the walls of the case, a latch pivoted to the inside of the wall of the case adjacent to a bent portion of the spindle, said latch having an offset part extending into the path of a bent portion of the spindle and means extending to the exterior into the path of the edge of the casing cover.

75

7. An inclosed switch comprising an enclosing case, an operating spindle supported by the walls of the case, said spindle having a crank section in the interior and a handle on the exterior of the case, and a pivoted latch having a part extending in the interior into the path of the crank and a part projecting to the exterior into the path of the edge of the casing cover, whereby the cover cannot be closed unless said latch 90 is in position to be engaged by the switch operating mechanism.

80

8. An inclosed switch comprising an enclosing case, an operating spindle supported by the walls of the case, said spindle having a crank section in the interior and a handle on the exterior of the case, and a latch pivoted inside of the case, said latch having a part projecting in the interior of the case into the path of the crank and adapted in one position to lock the crank and in another position to stop the crank, said latch also having a part projecting to the exterior of the case into the path of the edge of the casing cover.

95

9. An inclosed switch comprising an enclosing case, switch operating means, and means in the interior of the case adapted in one position to engage and limit the movement of the switch operating means and in another position to lock the switch operating mechanism against movement, said limiting means having a part that is engaged and held in both operative positions by the edge of the casing cover.

100

10. An inclosed switch comprising an enclosing case, switch operating means, and means adjustable to limit the opening movement of the switch operating means or prevent the closing movement of the switch operating means, said means having a part that projects into the path of the edge of the casing cover whereby the cover cannot be tightly closed unless the said limiting means is in functional position.

105

11. An inclosed switch comprising an enclosing case having a movable cover, switch operating means, and means adapted to be moved into position to limit the movement of the switch operating means, said latter

115

120

125

130

means preventing the closing of the casing cover unless in position to limit the movement of the operating means.

12. An inclosed switch comprising an enclosing case having a movable cover, switch operating means, a latch adapted to limit the movement of said operating means, and means associated with the latch, casing and cover to prevent the closing of the cover

unless the latch is in position to limit the 10 movement of the operating means.

13. An inclosed switch having external operating means, and means adapted to prevent the complete shutting of the closure unless said means is in position to limit 15 the movement of the operating means.

JOSEPH SACHS.
